UNITED STATES PATENT OFFICE.

FREDERICK L. SMITH, OF LANSING, MICHIGAN, ASSIGNOR TO OLDS MOTOR WORKS, OF LANSING, MICHIGAN, A CORPORATION OF MICHIGAN.

ADJUSTABLE STRAP-SECURING CLIP FOR VEHICLES.

No. 878,568.

Specification of Letters Patent.

Patented Feb. 11, 1908.

Application filed March 18, 1907. Serial No. 362,972.

To all whom it may concern:

Be it known that I, FREDERICK L. SMITH, a citizen of the United States of America, residing at Lansing, in the county of Ingham and State of Michigan, have invented certain new and useful Improvements in Adjustable Strap-Securing Clips for Vehicles, of which the following is a specification, reference being had therein to the accompanying drawings.

It is the object of the invention to facilitate the securing of packages, as, for instance, trunks, upon a vehicle, being more particularly designed for use in connection with automobiles.

The invention consists in the peculiar construction of a rail secured to the deck or floor of the vehicle, and a clip or eye adjustably secured to said rail, as hereinafter set forth.

In the drawings, Figure 1 is a plan view of an automobile body to which my improvements are applied; Fig. 2 is a cross section through one of the rails with a clip in engagement therewith; and Fig. 3 is a side elevation thereof.

A is the vehicle body, of any suitable construction, provided with a deck or flooring B.

C is a rail, preferably extending longitudinally of the deck, and a pair of such rails being preferably arranged parallel to each other at opposite ends of the deck. These rails C are preferably of T-shape cross section, having the opposite side flanges D D' secured to the flooring, and a central vertically slotted web E depending through the floor.

F is the clip, which is preferably in the form of an eye, having the shank G adapted to fit within the slot E' of the web E.

H is a head at the lower end of the shank G adapted to engage with the under face of the web E upon opposite sides of the slot therein. The rail C is provided at one end with an enlargement I of the slot E', which is of sufficient width for the insertion of the head H of the clip.

With a construction, as described, the clips, when engaged with the rail, may be readily adjusted longitudinally thereof by sliding the shanks G along the slots E'. When, however, the strap is secured to the

eye of the clip, and placed under tension by a pull in a direction oblique to the axis of the rail, the clip will be turned into a position where the head H will bind against the lower face of the rail, thereby frictionally holding the clip from displacement. The rails C, in addition to their function of engaging the clips F, also form wear-irons for protecting the floor or deck of the vehicle.

What I claim as my invention is:

1. The combination with a vehicle deck or flooring, of a rail extending longitudinally thereof, and a clip longitudinally slidable along said rail when in vertical position, and adapted to frictionally lock against the rail when in oblique position.

2. The combination with a vehicle deck or flooring, of a longitudinally slotted rail, extending along said flooring, a clip having a shank extending through said slot, and a head at the lower end of said shank for engaging the under face of the rail, substantially as, and for the purpose set forth.

3. The combination with a vehicle deck or flooring, of a longitudinally slotted rail extending along and secured to said flooring, and having an enlargement into said slot at one point in the length thereof, a clip provided with a downwardly extending headed shank, said shank being adapted to fit within said slot and said head to pass through the enlargement in said slot into engagement with the under side of the rail, substantially as, and for the purpose set forth.

4. The combination with a vehicle deck or flooring, of a rail of T-shape cross section, having the web portion thereof centrally slotted, said rail extending along said flooring and being secured thereto, and a clip having a downwardly extending shank slidably fitting the slot in said rail, and a head at the lower end of said shank for engaging the under face of the rail, substantially as, and for the purpose set forth.

In testimony whereof I affix my signature in presence of two witnesses.

FREDERICK L. SMITH.
